OSCAR C. KAVLE, OF SYRACUSE, NEW YORK, ASSIGNOR TO HARVEY A. MOYER, OF SYRACUSE, NEW YORK.

TABULATING MECHANISM FOR TYPE-WRITING MACHINES.

1,013,020.

Specification of Letters Patent. Patented Dec. 26, 1911.

Application filed May 27, 1907. Serial No. 375,781.

To all whom it may concern:

Be it known that I, OSCAR C. KAVLE, a citizen of the United States, residing at Syracuse, in the county of Onondaga and State of New York, have invented a new and useful Improvement in Tabulating Mechanisms for Type-Writing Machines, of which the following is a specification.

This invention relates to tabulating mechanisms for typewriting machines whereby the paper carriage can be quickly stopped at predetermined desired points for the production of tabulated or column work.

The primary objects of the invention are to produce an efficient tabulating mechanism giving increased speed and certainty of action with the minimum strain and wear thereon and on the typewriter; also to so construct the mechanism that the carriage can move rapidly and will be stopped with the minimum shock and will be prevented from rebounding; also to make the mechanism of strong, durable and inexpensive construction; and also to improve tabulating mechanisms in the respects herein-after described and set forth in the claims.

In the accompanying drawings, consisting of two sheets: Figure 1 is a fragmentary longitudinal sectional elevation of a type-writing machine provided with tabulating mechanism embodying the invention, in line 1-1, Fig. 9. Fig. 2 is a similar fragmentary view of the tabulating mechanism, showing a different position of the parts.

Figs. 3 and 4 are fragmentary sectional elevations thereof in line 3-3, Fig. 9, showing two other successive positions of the stop devices. Fig. 5 is a perspective view, on an enlarged scale, of the stationary stop lever detached. Fig. 6 is a plan view of the blank from which the stationary stop lever is made. Figs. 7 and 8 are plan views, on an enlarged scale, of the stop device and the coöperating guide plate, showing two positions of the stop lever. Fig. 9 is a rear elevation of the tabulating mechanism and upper portion of the typewriter. Fig. 10 is a plan view, partly broken away, thereof. Fig. 11 is a fragmentary rear elevation thereof, partly in section, in line 11-11, Fig. 10. Fig. 12 is a horizontal sectional plan thereof in line 12-12, Fig. 11. Fig. 13 is a

detail sectional elevation showing a modification of the stop.

Like letters of reference refer to like parts in the several figures.

The invention is illustrated in connection with a visible writing typewriting machine in which the type strike, on the front side of the platen and in which the platen is shiftable vertically for printing upper and lower case characters, but the improvements are also applicable to other kinds of type writing machines.

A, Fig. 1, represents a portion of the main frame, B the platen, C the platen carriage, and D a shift frame on which the carriage is supported and moved transversely of the machine by usual means not shown, and E which is pivoted at opposite sides at d to suitable portions at the upper rear part of the main frame to swing vertically for shifting the platen. The carriage, as usual, is provided with a rack bar E meshing with a pinion e governed by an ordinary escapement mechanism (of which the wheel e' connected to the shaft of the pinion e is a part) for effecting the step-by-step, or letter space movements, of the carriage. These parts, with the exception of the rack, which is preferably constructed as presently described, may all be of known or any suitable construction.

The rack bar shown consists of an angular strip secured by screws, or otherwise, to a flat-sided cylindrical rod, and is provided with a toothed lower edge for engagement with the escapement pinion and a serrated upper edge for holding the traveling stop device in different desired positions. The upper face of the rack strip is provided with a graduated scale for facilitating the adjustments of the stop device; see Fig. 10. The rack bar is secured at opposite ends to the usual carriage release levers e' fulcrumed at e² on the ends of the carriage. As usual, in tabulating mechanisms, the irregular movements of the carriage necessary for tabulated work are effected by releasing the carriage from the controlling escapement and providing one or more stop devices on the carriage adapted to strike a coöperating relatively fixed stop device to arrest the carriage at the desired point or points. For

clearness of description the stop device F on the carriage will be herein termed the "movable stop" and the coöperating stop device G, which is mounted on the shift frame, will be termed the "stop."

Any desired number of the movable stops may be employed, depending upon the requirements of the machine. Two are shown in the drawings, which are alike. Each 10 movable stop is retained on the rack bar by a segmental cylindrical socket embracing the cylindrical rod of the rack bar, from which it extends rearwardly, and has teeth f, Fig. 9, to engage the serrated upper edge of the 15 rack bar to hold it in adjusted position. The movable stop can be pushed along the rod to any desired position by first swinging it upwardly to disengage its teeth from the serrated edge of the rack bar, and preferably the socket of the stop is of spring 20 temper and grips the supporting rod with sufficient force to hold the stop stationary at any desired point thereon when swung up out of engagement with the serrated 25 edge of the rack bar. When the tabulator is not in use, the movable stops are thus swung up out of operative position. The free end of the movable stop, which extends rearwardly beyond the rack bar, is provided 30 with an upturned hook or projection f' for a purpose which will appear later. The rack bar could be of other construction and the movable stops adjustably secured thereto in any other suitable manner.

35 The stop G on the shift frame consists of a substantially upright lever provided at its upper free end with a guide lug or finger g, and below this with laterally projecting rearwardly and forwardly opening hooks 40 g' g'', respectively, one below the other, see Figs. 1-8, these parts being for a purpose to be explained. The stop lever can be conveniently formed from a sheet metal blank of the shape shown in Fig. 6, by bending 45 the parts g' and g'' thereof to form its lateral hooks. The stop is pinned or otherwise secured to a horizontal rock shaft H journaled at its ends in suitable bearings h h', Figs. 9 and 11, on the shift frame, and 50 stands beside an upright post h² on the shift frame. When the movable stop strikes the stop G to arrest the carriage, it forces the same against the post h² which thus braces the stop and prevents injury thereto. The 55 stop G is swung forwardly and rearwardly and out of the path of the movable stops by rocking the rock shaft H. For operating the rock shaft it is preferably provided near its outer end with an arm h³ connected by 60 a link i to a lever i' pivoted on the main frame beneath the top plate and connected by a rod i² to a tabulator key lever I which is fulcrumed on the frame and extends forwardly to the keyboard. The rock shaft is 65 held in normal position and returned to

such position after actuation by a suitable spring, such as the spring i³, Fig. 9, surrounding the rock shaft and connected thereto and bearing against an adjacent part of the shift frame. The link i connecting the rock arm h³ to the lever i' is preferably so arranged that in the normal position of the shift frame, shown in Fig. 1, it inclines rearwardly from a line passing through the pivotal axis of the shift frame and the pivot joining the link to the lever i', whereas when the shift frame is raised to shift the platen, it swings across such line and inclines forwardly therefrom, so that the same depression of the tabulator key I will produce equal movements of the rock shaft in both positions of the shift frame.

h is a rock arm extending forwardly from the rock shaft over one end of a rack releasing lever K, Figs. 10-12, which is fulcrumed by a suitable pivot h' on the shift frame and is provided at its other end with a rounded projection h² adapted to engage the rack bar to lift the same out of engagement with the escapement pinion without preventing the horizontal movement of the rack bar and carriage.

L represents an arm projecting rearwardly from the rock shaft for engaging the escapement wheel e' and holding it from 95 backward movement when the rack bar is released from the pinion e.

M represents a guide plate which is fixed to the upper end of the post h² on the shift frame. This plate, see Figs. 7 and 8, is provided with a slot m in which the finger g on the upper end of the stop lever G engages and slides forwardly and rearwardly, and at one side of the front end of said slot with a shoulder or notch m' for receiving the finger to lock the stop lever in the forward position shown in Figs. 2 and 7. The stop lever is made of spring metal, or other means are provided tending to move the lever laterally toward said locking notch so that when the finger at its upper end leaves the guide slot m it will spring into said notch to lock the stop forward.

The stop lever made of spring metal is an inexpensive and desirable construction, but if preferred, a stop G', Fig. 13, pivoted or otherwise mounted to move laterally and having a separate spring g³ for so moving it, could be employed.

The operation of the tabulating mechanism as thus far described is as follows: When it is desired to use the mechanism the movable stops are adjusted to the proper positions lengthwise along the carriage, as indicated by the scale on the rack bar, depending upon the points at which it is desired to stop the carriage, and their teeth engaged with the serrated edge of the rack bar. The normal position of the parts is shown in Fig. 1, from which it will be seen

that the rack bar can be oscillated on its pivots e^3 in the normal use of the machine without the movable stops interfering with the fixed stop G . Any stops not required are turned up as indicated by broken lines in Fig. 1. The depression of the tabulator key I , through the described connections, rocks the shaft H and swings the rack releasing lever K on its fulcrum, thereby lifting the rack bar out of engagement with the escapement pinion and at the same time swinging the stop G forwardly into the path of the movable stop. The carriage being then released from the escapement is moved to the left by its driving spring until arrested by the engagement of the movable stop with the stop G . The hooked rear end of the movable stop strikes the stop G between the two hooks g' and g^2 thereof, the parts then being in the position shown in Fig. 2. When the stop moves forwardly to intercept the movable stop, it springs away from the post h^2 and its finger g snaps into the locking notch m' , which holds it forward with its rearwardly opening hook g' in front of the path of movement of the hook on the movable stop, and locks the parts in the position shown in Fig. 2. This action is desirable as it enables the operator to depress the tabulator key with the quick movement required for the type-bar keys and relieves him of the necessity of holding the key down until the carriage has completed its movement. It also prevents injury to the parts by insuring the proper contact of the stops. When the stop G is struck by the movable stop it is released from the locking notch m' and pressed over against the post h^2 in opposition to its spring action, which serves to cushion the blow of the carriage, thereby reducing the shock, noise and wear of the parts to an important degree. The stop being thus disengaged from its holding notch and its finger g brought opposite to the guide slot m in the plate M , it will be moved rearwardly in said slot by the return spring i^3 for the rock shaft H until its rearwardly opening hook g' engages the hook of the movable stop, as shown in Fig. 3, which locks the carriage against rebounding, or insures the retention thereof at the exact letter space for which the stop is set. Thus a most serious objection to many tabulators is overcome. This partial return of the stop G frees the rack releasing lever K and permits the rack bar to fall enough for the hook of the movable stop to clear the rearwardly opening hook g' and drop beside the forwardly opening hook g^2 of the stop G ; as shown in Fig. 4, which allows the stop G to complete its rearward or return movement but acts as a guard to prevent the carriage from rebounding during the slight interval of time required for the stop G to reach its

initial position. This hook g^2 is not so essential as the other hook g' but affords an additional safeguard against the rebounding of the carriage. When the stop G is fully retracted, the parts will be again in the normal position, shown in Fig. 1, and the carriage under the control of the escapement so that the writing can be done.

From the above description it will be seen that the stop G is advanced with two motions, first forwardly and then laterally, and that it returns with three motions, first laterally and then backwardly, coming to a stop so as to divide the backward movement into two steps. Thus, in effect, a maze is formed through which the movable stop must find its way in two directions with a rest or dwell before it can resume the normal position, which allows a quicker action of the tabulator key, prevents rebounding of the carriage and greatly reduces noise and wear.

Preferably the strength of the spring operating the stop G is such that the carriage spring will hold the stop against the post h^2 , but as the return spring i^3 for the rock shaft H draws the stop back into the guide slot before the carriage has time to rebound, a stop spring of greater strength than the carriage driving spring could be employed. In such case, however, the return spring i^3 for the rock shaft would have to be correspondingly heavier.

The stop devices constructed and operating as described are not dependent upon the particular manner of mounting them and the particular connections for swinging the stop G and releasing the carriage, and other means can be employed for these purposes. Furthermore, the interlocking hook construction of the stops would be desirable with a rigid or non-yielding stop G .

The mechanism as described is effective for use with a light carriage, or for a heavy carriage if the stops are arranged at comparatively short intervals, but for the most perfect action this mechanism is supplemented by a speed controller which allows the carriage to jump over long spaces without severe shock or excessive wear on the parts.

The speed controller preferably consists of a rotary governor fan with speed gearing driven by the rack bar which regulates the speed of the carriage.

N represents the fan consisting of a metal plate provided centrally with a sleeve or hub, which is journaled to rotate on an extension of the pivot h' for the rack releasing lever K , on which it is held by a screw n , or otherwise. A pinion O formed on or secured to the fan hub meshes with a gear wheel p , secured to one end of a shaft p' which is journaled in a suitable bearing on the releasing lever K and is provided at its

other end with a pinion p^2 . This pinion is normally below and out of contact with the teeth of the rack bar, but when the releasing lever K is moved to lift the rack bar from the escapement pinion, the pinion p^2 is lifted into mesh with the rack bar teeth before the latter clear the escapement pinion, so that as the rack bar moves forward with the carriage the gear train is operated and the fan rotated rapidly enough for the air resistance to prevent excessive speed of the carriage. This controller is of simple and light construction, is noiseless in use, and as the air forms the resisting medium, and it is not affected by changes in temperature, dirt, oil and other conditions that interfere with the proper action of governors depending upon friction, spring action and centrifugal force. There is also less friction and wear on the parts and the wear cannot interfere with its action so as to require readjustment. This fan governor could be used to advantage with tabulating mechanisms of other construction, and, as before stated, the described tabulating mechanism would be useful without a speed controller or governor.

I claim as my invention:

1. In a typewriting machine, the combination of a carriage, a rack-bar movably mounted on the carriage, one or more stops on said rack-bar, a coöperating stop, and means for moving both stops transversely of the direction of movement of the carriage into position for one to strike the other in the movement of the carriage, substantially as set forth.
2. In a typewriting machine, the combination of a carriage, an escapement therefor, a stop traveling with the carriage, a coöperating stop, means for releasing the carriage from the escapement and causing one of said stops to strike the other in the movement of the carriage, both of said stops being movable transversely of the direction of movement of the carriage for first interlocking with each other to prevent the rebound of the carriage and then clearing each other, substantially as set forth.
3. In a typewriting machine, the combination of a carriage, a rack-bar pivoted thereon, a series of adjustable stops on said rack-bar, a movable shift frame for the carriage, a stop on said shift frame, and means for moving both stops transversely of the direction of movement of the carriage into position for one to strike the other in the movement of the carriage, substantially as set forth.
4. In a typewriting machine, the combination of a carriage, a rack bar movable therewith and transversely movable thereon, one or more adjustable stops on said rack-bar and movable with the carriage, and a

yielding stop for intercepting the adjustable stop, substantially as set forth.

5. In a typewriting machine, the combination of a carriage, an escapement therefor, one or more stops movably mounted on and movable with the carriage, a pivoted yielding stop normally out of the line of movement of said movable stops, and means for moving both stops transversely of the direction of movement of the carriage into position for one to strike the other in the movement of the carriage, substantially as set forth.

6. In a typewriting machine, the combination of a carriage, one or more stops movable with the carriage, a coöperating stop, and means for moving said stops into intercepting position, said stops being constructed to interlock with each other to prevent the rebounding of the carriage and the immediate return of the stops to the normal position, substantially as set forth.

7. In a typewriting machine, the combination of a carriage, a bar thereon, a series of adjustable stops supported thereby, a stop constructed to intercept either of the adjustable stops and automatically interlock therewith, and means for moving said stops into intercepting position, substantially as set forth.

8. In a typewriting machine, the combination of a carriage, one or more stops movably mounted thereon, a movable shift frame for the carriage, a coöperating stop supported by the shift frame, means for moving both stops into position to engage each other by the movement of the carriage, and an automatic latch for retaining said stops in such position regardless of the moving means until the stops engage and then releasing the stops, substantially as set forth.

9. In a typewriting machine, the combination of a carriage, one or more stops movable thereon transversely of the direction of movement of the carriage, a coöperating stop which intercepts and interlocks with said carriage stop and retains such interlocking engagement until the carriage stop moves transversely to the line of the carriage movement, and means for moving the coöperating stop into engaging position, substantially as set forth.

10. In a typewriting machine, the combination of a carriage, one or more stops movable thereon transversely of the direction of movement of the carriage, and a manually-operated coöperating stop which intercepts the carriage stop and interlocks therewith to prevent the rebounding of the carriage, said carriage stop being released by its transverse movement from said other stop, and means for automatically returning both stops to their normal positions, substantially as set forth.

11. In a typewriting machine, the combination of a carriage, a stop movable therewith, a coöperating stop, means for moving said coöperating stop into the path of movement of said stop on the carriage, and means for moving said coöperating stop to cause it to temporarily interlock with said carriage stop after said stops contact, said carriage stop being movable on the carriage to release it from interlocking engagement with said coöperating stop and permit the latter to move out of the path of said stop on the carriage, substantially as set forth. 70
12. In a typewriting machine, the combination of a carriage, one or more carriage stops movable with the carriage, a coöperating intercepting stop constructed to arrest either of the carriage stops, said carriage and intercepting stops being relatively movable to temporarily hold the carriage stop against movement either forwardly or backwardly, substantially as set forth. 75
13. In a typewriting machine, the combination of a carriage, one or more stops movable with the carriage, and an intercepting stop which the movable stops pass by movements in two directions, substantially as set forth. 80
14. In a typewriting machine, the combination of a carriage, a stop movable with the carriage, and an intercepting stop, said stops having an interlocking construction requiring an intermittent motion of each stop to enable one stop to clear the other, substantially as set forth. 85
15. In a typewriting machine, the combination of a carriage, a bar thereon and moving therewith, a stop supported by and moving with said bar, an intercepting stop normally stationary and out of the line of movement of the movable stop, and means for moving the stationary stop into line with the movable stop, the stops acting to first contact on said line and interlock thereon, and then to unlock in returning to their normal positions, substantially as set forth. 90
16. In a typewriting machine, the combination of a carriage, a stop movable with the carriage, and an intercepting stop having a pair of opposable hooks through which the movable stop passes after having been intercepted, substantially as set forth. 95
17. In a typewriting machine, the combination of a carriage, coöperating stops therefor, one of which is movable with the carriage, means for moving said stops transversely of the direction of movement of the carriage into intercepting position, one of said stops having oppositely directed hooks, and the other having a hook arranged to pass between and interlock successively with the two hooks on the first stop, substantially as set forth. 100
18. In a typewriting machine, the combination of a shift frame, a carriage sup- 130
- ported by the shift frame, a rack-bar on the carriage, one or more stops carried by said rack-bar, an escapement wheel on the shift frame, a rock shaft on the shift frame, and a pair of stops on the rock shaft acting to intercept the carriage stops and escapement wheel, substantially as set forth. 105
19. In a typewriting machine, the combination of a shift frame, a carriage supported by the shift frame, a rack-bar on the carriage, one or more stops carried by said rack-bar, an escapement wheel on the shift frame having connection with the rack-bar, a rock shaft on the shift frame, and three arms on the rock shaft acting to release the rack-bar from the escapement wheel, intercept said stops on the carriage, and lock the wheel against backward movement, substantially as set forth. 110
20. In a typewriting machine, a tabulator stop bar having a serrated portion and a portion of segmental circular cross-section, and a stop device having an extending rigid part forming a stop and provided with a tooth to engage the serrations of the bar and integral spring jaws which grasp the segmental circular portion of the stop bar and permit the stop device to be turned thereon to move its tooth into and out of engagement with said serrations, substantially as set forth. 115
21. In a typewriting machine, the combination with the carriage, of an escapement wheel for the carriage, a rack-bar controlled by said wheel, a rock shaft having a pair of projecting arms one acting to release the rack-bar from the escapement wheel and the other acting to lock said wheel, and means for rocking said shaft, substantially as set forth. 120
22. In a typewriting machine, the combination of a main frame, a carriage, a shift frame for the carriage pivotally supported by the main frame, coöperating tabulating stops supported by the carriage and the shift frame, a tabulator key or lever supported by the main frame, and connecting means between the key and the stop on the shift frame whereby said stop is caused to move substantially the same distance with the shift frame in either of its positions, substantially as set forth. 125
23. In a typewriting machine, the combination of a main frame, a carriage shift frame pivoted on the main frame, a tabulator stop supported by the shift frame, a tabulator key or lever supported by the main frame, and a link having a pivotal connection at one end with the key and at the other end with the stop, the end of the link connected to the stop being arranged to swing over a line passing through the pivotal connection at the other end of said link and the pivotal axis of the shift frame, substantially as set forth. 130

24. In a typewriting machine tabulating mechanism, the combination of a carriage, an escapement mechanism therefor, a rack-bar normally in operative connection with said escapement mechanism for controlling the movement of the carriage, a lever for releasing said rack-bar from the escapement mechanism, a rotary fan for controlling the speed of the carriage when the rack-bar is released from the escapement mechanism, and gearing which is carried by said lever and is placed in driving engagement with said rack-bar by the movement of said lever to release the rack bar from the escapement mechanism, substantially as set forth.

25. In a typewriting machine tabulating mechanism, the combination of a carriage, an escapement mechanism therefor, a rack-bar normally in operative connection with

said escapement mechanism for controlling the movement of the carriage, a lever for releasing said rack-bar from the escapement mechanism, a rotary fan for controlling the speed of the carriage when the rack-bar is released from the escapement mechanism, said fan being journaled concentrically with the pivot for said lever, and gearing which is carried by said lever and is placed in driving engagement with said rack-bar by the movement of said lever to release the rack-bar from the escapement mechanism, substantially as set forth.

Witness my hand, this 23rd day of May, 1907.

OSCAR C. KAVLE.
